UNITED STATES PATENT OFFICE.

HENRY ASHWORTH, OF OLLERTON, EAGLEY, NEAR BOLTON, COUNTY OF LANCASTER, ENGLAND.

SPINNING-MULE.

SPECIFICATION forming part of Letters Patent No. 390,549, dated October 2, 1888.

Application filed December 31, 1887. Serial No. 259,491. (No model.) Patented in England December 11, 1886, No. 16,250.

To all whom it may concern:

Be it known that I, HENRY ASHWORTH, of Ollerton, Eagley, near Bolton, in the county of Lancaster, England, have invented new and 5 useful Improvements in Spinning-Mules, (for which I have obtained a patent in Great Britain, dated December 11, 1886, No. 16,250,) of which the following is a specification.

This invention relates to mules for spinning; 10 and it consists in the construction and combination of devices hereinafter described and claimed.

Figure 1 is a longitudinal sectional side elevation of a part of a mule-carriage, showing the 15 center lines of the double row of spindles parallel with each other and illustrating the operation of spinning. Fig. 2 is a sectional side elevation of the mule-carriage when commencing to make the outward run during the 20 operation of spinning.

A A are the ordinary rollers mounted on the roller-beam.

B is the mule-carriage, which is of the ordinary construction.

25 C C show the spindle-box, constructed to carry two rows of spindles.

D is a mule-spindle in the row nearest the roller-beam or rollers A, and E is a mule-spindle in the outer row, or the farthest from 30 the rollers A.

F F are the coppering faller-rods, and G G are the under faller-rods. On the coppering faller-rods F F are mounted the sickles H H, carrying the coppering faller-wires I I. The under 35 faller-rods, G G, are fitted with the sickles J J, carrying the under faller-wires, K K. Motion is imparted to the coppering and under fallers by the ordinary means, the under fallers being weighted and regulated in the usual manner.

40 The double set of coppering and under faller-rods are coupled, as in Fig. 1, by which a simultaneous motion will be given to each to produce uniform cops on each row of spindles, and by which only one coppering motion will be 45 requisite to operate the same.

As shown, the spindles D and E are placed parallel to each other in the spindle-box C on the mule-carriage B, the outer row of spindles E being set higher than the spindles D, to al-

low of the faller-wires I and K performing 50 their respective movements without clashing or interfering with each other's yarn when being delivered to both rows of spindles from one set of rollers A. To enable the yarn from one set of rollers A to be delivered on both rows 55 of spindles alike, I utilize the under faller, K, on the sickle J to guide it to the spindle E, as shown in Fig. 2, the angle of the yarn from the under faller, K, to the point of the spindle E being parallel with the angle of the yarn 60 from the rollers A to the point of the spindle D, thereby producing uniform cops on each row 65 of spindles, which is effected by attaching the curved projection S on the roller-beam T to lift the under faller-wires, K, when the mule-carriage is just completing the inward run, so as to be ready when spinning commences.

The double set of coppering and under fallers are coupled by levers V, the latter being connected by the socket W and screw Z, which 70 will allow of the fallers being adjusted to the greatest nicety, the screw Z being locked by the nut O, as shown in Fig. 1.

Having now particularly described and ascertained the nature of my said invention and 75 in what manner the same is to be performed, I declare that what I claim is—

1. The combination of the rollers A A, the mule-carriage B, the double row of spindles D E, arranged at different heights, the coppering 80 faller-rods F F, the under faller-rods, G G, the sickles H H, carrying the coppering faller-wires I I, the sickles J J, carrying the under faller-wires, K K, and the roller-beam T, having a projection, S, to lift the under faller-wires, substantially as described.

2. The combination of the double row of spindles D E, the fallers and faller-wires, the coppering faller-rods F F, the under faller-rods, G G, the levers V, sockets W, screws Z, and 90 nuts O, substantially as described.

In testimony whereof I affix my signature in presence of two witnesses.

HENRY ASHWORTH.
